Primary Examiner—Charles A. Rademaker

(74) *Attorney, Agent, or Firm*—MacPherson Kwok Chen & Heid LLP; Tom Chen

(57) **CLAIM**

The ornamental design for a wireless access point, as shown and described.

DESCRIPTION

FIG. 1 is a perspective view of a wireless router showing our new design;

FIG. 2 is a top plan view thereof;

FIG. 3 is a front elevation thereof;

FIG. 4 is a side elevation thereof; and,

FIG. 5 is a rear elevation view thereof.

The broken line showing of portions of the design is included for the purpose of illustrating environmental structure and forms no part of the claimed design.

1 Claim, 5 Drawing Sheets
